UNITED STATES PATENT OFFICE.

HERMAN J. JAEGER, OF NEW YORK, N. Y

INCANDESCENT ELECTRIC LAMP.

No. 905,703.

Specification of Letters Patent.

Patented Dec. 1, 1908.

Application filed November 4, 1907. Serial No. 400,435.

To all whom it may concern:

Be it known that I, HERMAN J. JAEGER, a citizen of the United States of America, and a resident of New York, in the county and State of New York, have invented certain new and useful Improvements in Incandescent Electric Lamps, of which the following is a specification.

This invention has reference to improvements in incandescent electric lamps.

It pertains particularly to that type of incandescent electric lamps containing a so called metallic filament of relatively great length embodied in a glass globe of usual size and having a number of loops all in series with each other. Thus the loops of the filament form one continuous single conductor requiring but two leading-in wires like in any ordinary multiple arc lamp. Such long metallic filaments for incandescent electric lamps, for instance, the so called tungsten or wolfram filament expands by the heat of the electric current when the lamp is lighted. Each loop of the filament accordingly gets longer and at the same time softens to a certain degree. Therefore lamps containing such filaments can not be burned safely except when the lamp hangs vertically downward with the base at the top and then there is danger of two neighboring loops coming in contact with each other whereby the filament burns out or one loop may touch the glass wall breaking same and destroying the vacuum. In case lamps are mounted with the base at the bottom and the filament at the top the danger of loosening the lamp is so much greater. For certain purposes it is desirable or necessary to mount lamps so that the filament is in a horizontal position. Lamps of the type described cannot be used at all for such purposes. In order to render it possible to use such long tungsten or wolfram filaments in lamps which are horizontally mounted a substantial support for the filament must be provided within the lamp. The usual anchors heretofore employed for supporting filaments will not answer for this purpose for economic reasons because too many of them would be necessary to support say, a four loop filament and such anchors are made of platinum wire which is very expensive.

My novel incandescent lamp which forms the subject matter of this invention overcomes the described deficiencies as will be

fully explained further down in connection with the accompanying drawing in which:

Figure 1 represents in elevation an incandescent lamp embodying in desirable form the present improvements. Fig. 2 illustrates in top plan view part of the support and the top portions of the loops of the filament, and Fig. 3 is a like view on line 3, 3 of Fig. 1.

Similar letters of reference denote like parts in all the figures.

The present improvements may be applied to any kind or style of incandescent lamps. It is however preferred to embody the improvements in the so called well known tipless lamps.

In Fig. 1 of the drawing *a* represents the lamp globe or vacuum chamber which necessarily is of elongated or pear shape, *b* is the stem sealed into the globe in the usual manner and carrying the conducting wires *c*, *d*, which are sealed into the top portion of the stem. To the solid top portion of the stem is fused a post or standard *e* consisting preferably of a thin glass rod. A disk of mica *f* is cemented to the lower portion of the standard *e* having a multiple of small openings of even number near its circumference. A like mica disk *g* is cemented to the top portion of the standard *e* having a like multiple of openings *h*, of even number shown in Fig. 2 and corresponding and coinciding with the openings in the mica disk *f*. The standard *e* and the mica disks *f* and *g* form the support for the long filament, each loop passing through two neighboring openings *h*. Four loops are represented on the drawing and therefore eight openings must be in each mica disk. The lower ends of the filament loops *i* are cemented in the openings of the lower disk *f* and the adjoining ends of two neighboring loops are connected by a short bridge *j* with the exception of one pair of such ends of two neighboring loops which pass through the disk *f* and are cemented to the ends of the platinum wires which are bent horizontally over and again upward to meet the ends of the one pair of loops as shown at *k*.

In the described manner one continuous long compound filament is formed out of the four loops and the current passing in through the one wire passes successively through the four loops and returns through the second wire. The four loops are loosely passing through the openings in the top disk *g* allow-

2
ing thus of linear expansion when they become incandescent. The short bridges *j* are made of any suitable material such as pieces of carbon filament of sufficiently low resistance or of platinum wire. The bridges *j* bear against the lower disk *f* and their ends are practically cemented thereto in the place where same are cemented to the loop ends which are tight in the openings of the disk *f* 10 as shown in Fig. 3.

As above described the supporting disks *f* and *g* are preferably made of mica. The disks are carefully freed from gases so that they do not give up enough gas during 15 the burning of the lamp to injure the filament but this process does not form part of this invention. Any other non-conducting material which does not give up gases may be used in place of mica, for instance, very thin 20 glass plates but these are not so easily handled and the openings made so conveniently. Two of the described disks are shown on the drawing but three or more may also be employed in lamps of considerable length such 25 as the so called glass tube lamps.

The filament loops of tungsten or wolfram supported by the described devices do not sag, only linear expansion takes place during the burning of the lamp and the natural life 30 of the lamp is neither impaired nor the filament injured.

Having thus described my invention I claim as new and desire to secure by Letters Patent:

35 1. An incandescent electric lamp comprising a vacuum chamber with stem and leading-in wires, a thin long standard fused to the top portion of the stem, insulating disks attached at suitable intervals to said standard having each a multiple of small openings 40 of even number near the circumference which coincide with each other, and a long metallic compound filament consisting of a multiple of loops in said openings cemented with their 45 open ends in the openings of the disk near the

stem and allowing of linear expansion, conducting bridges cemented each to two adjoining ends of two neighboring loops on the disk near the stem leaving two such ends free which pass through said disk and connect one each with one of the leading-in wires. 50

2. In an incandescent electric lamp of the type described a stem with leading-in wires, a thin long glass rod fused to the top portion of the stem, mica disks attached at suitable 55 intervals to said standard having each a multiple of small openings of even number near the circumference which coincide with each other, and a long metallic compound filament in said openings consisting of a multiple of 60 loops cemented with their open ends in the openings of the disk near the stem and allowing of linear expansion, conducting bridges cemented each to two adjoining ends of two neighboring loops on the disk near the stem 65 leaving two such ends free which pass through said disk and connect one each with one of the leading-in wires.

3. In an incandescent lamp of the type described a thin glass rod, mica disks attached 70 at suitable intervals to said standard having each a multiple of small openings of even number near the circumference which coincide with each other, and a long metallic filament in said openings consisting of a multiple 75 of loops cemented with their open ends in the openings of the disk near the stem and allowing of linear expansion, conducting bridges cemented each to two adjoining ends of two neighboring loops on the disk near the stem 80 leaving two such ends free which pass through said disk and connect one each with one of the leading-in wires.

Signed at New York, N. Y., this 2nd day of November, 1907.

HERMAN J. JAEGER.
